UNITED STATES PATENT OFFICE.

GEORGE KIERNAN, OF PHILADELPHIA, PENNSYLVANIA.

DESIGN FOR A DARNING-LAST.

45,996.

Specification for Design.

Patented June 23, 1914.

Application filed April 11, 1914. Serial No. 831,350. Term of patent 14 years.

To all whom it may concern:

Be it known that I, GEORGE KIERNAN, a citizen of the United States of America, residing at Philadelphia, in the county of Philadelphia and State of Pennsylvania, have invented a new, original, and ornamental Design for Darning-Lasts, of which the following is a specification, reference being had to the accompanying drawing, forming part thereof.

Of the drawings: Figure 1 is an eleva-

tion, Fig. 2 is a section, and Fig. 3 is a plan view, of a darning last, showing my new design.

I claim:

The ornamental design for a darning last, as shown.

GEORGE KIERNAN.
